GEORGE D. CASSON AND FRANK D. BLAKELY, OF WINNIPEG, MANITOBA, CANADA.

INTERNAL-COMBUSTION ENGINE.

1,107,895.

Specification of Letters Patent. Patented Aug. 18, 1914.

Application filed November 8, 1912. Serial No. 730,169.

To all whom it may concern:

Be it known that we, GEORGE D. CASSON and FRANK D. BLAKELY, citizens of Great Britain, and residents of Winnipeg, in the Province of Manitoba and Dominion of Canada, have invented a new and Improved Internal-Combustion Engine, of which the following is a full, clear, and exact description.

Our invention relates to internal combustion engines, and it comprises certain improvements in valve constructions for such motors, by means of which the entrance of the combustible gaseous mixture to the firing chamber and the discharge of the burnt mixture after explosion from the firing chamber can be more advantageously controlled.

Reference is to be had to the accompanying drawings forming a part of this specification, in which the same characters of reference indicate the same parts in all the views.

Figure 1 represents a transverse vertical sectional view of our improved engine, showing the valve-controlled devices therefor; Fig. 2 is a horizontal sectional view on the line 2—2 of Fig. 3; Fig. 3 is a side elevation of the valve tube or sleeve for the engine; and Fig. 4 is a vertical transverse sectional view of a modification.

Our improved engine as shown on the drawings comprises a cylinder 1 provided with a water jacket 2 and closed at one end by means of a head 3, which is bolted to the end of the cylinder or otherwise secured in position. At its other end the cylinder 1 is connected to a crank case 4, in which is located the power shaft through which power is transmitted. The opposite end of the cylinder, namely, the end to which the head 3 is applied, is of course the working end, and this head carries any convenient form of igniter shown at 5. Inside of the cylinder is the working piston 6, and 7 is a rod which connects the piston 6 to the crank 8 on the power shaft 9. This crank 8 and power shaft 9 are of course located in the crank case 4, and suitable bearings are provided in which the shaft 9 is mounted.

The numeral 10 represents the inlet port to the interior of the cylinder 1, this inlet port communicating with a mixture supply conduit 11, and the numeral 12 represents the exhaust port communicating with the exhaust conduit 13. The exhaust port is preferably located nearer to the head 3 than the port 10 for a purpose which will appear later.

The intake of mixture and outflow of gases from the cylinder 1 are controlled by means of a valve tube or sleeve shown at 14, which is disposed between the piston and the inner surface of the cylinder 1, and is designed to be rotated around the longitudinal axis of the cylinder, while at the same time permitting the piston 6 to reciprocate freely within the sleeve 14. The sleeve is rotated by means of a gear or pinion 15 on the shaft 9, meshing with a similar gear 16 mounted upon a way shaft 17. This shaft also carries a miter gear 18 which meshes with another miter gear 19 mounted upon a shaft 20. This shaft is carried in a suitable bearing in the casing 4, and likewise rotates a pinion 21. This pinion meshes with gear teeth 22 at the inner end of the sleeve 14, and the diameters of the pinion 21 and gear 22 are such that the pinion 21 will have to make two revolutions for one revolution of the sleeve 14, the engine being of the four-cycle type. The end of the sleeve 14 adjacent the head 3 is provided with a flange 23, which may be made integral therewith or separate therefrom, but secured thereon in any desired way. This flange rests upon the end of the cylinder, the head 3 being hollow, so as to provide a shoulder against which the flange 23 can abut. A similar flange 23 is disposed at the other end of the sleeve 14 between the casing and the gear 22. The upper flange 23 bears the stress when the piston is moving downward, and the lower flange 23 bears the stress when the piston is moving upward.

The sleeve 14 is provided with ports 24 and 25. These ports are arranged with their centers preferably 90° apart and in different transverse planes, the port 25 being nearer the upper flange 23 than the port 24. The port 24 is designed to register with the inlet port 10 in the cylinder wall, and the port 25 with the outlet port 12. The direction of rotation of the sleeve is shown by the arrow in Fig. 3, and it will be seen that with the ports 10 and 12 arranged at diametrically opposite points in the wall of the cylinder the inlet ports 10 and 24 will come into registry at the proper time after the outlet ports 25 and 12 move out of communication with one another at the close of the exhaust stroke, to allow the mixture to enter the firing chamber when the piston 6 moves outward.

The manner of operation of our engine

will be apparent. The direction of revolution of the crank shaft being as shown by the arrow in Fig. 1, motion will be transmitted to the gear 22 to turn the sleeve 14 in the cylinder 1 and around the piston 6. At the same time, the piston will be allowed to reciprocate freely, and mixture will flow in when the ports 24 and 10 are in communication, these two ports moving out of registration when the compression stroke commences, and the sleeve 14 closing the interior of the cylinder entirely on the compression and ignition strokes, and allowing the exhaust to commence at the end of the firing stroke by the port 25 coming into communication with the port 12. These operations are repeated for every cycle when the engine is running.

The sleeve 14 is further provided with a spiral groove 26 on its outer surface. This groove is an oil groove and carries a lubricant from the bottom of the cylinder and the inner end of the sleeve 14 up toward the top.

Fig. 4 illustrates a modification in which the sleeve 14 has an annular interior space 27 through which a cooling agent can be circulated. At the crank case end of the cylinder is provided a number of ports 28 which register with similar ports 29 leading to the space 27, and 30 is a similar port leading to ports 31 near the head 3, through which the cooling agent can be discharged. This cooling agent may be air or a suitable liquid, and it is taken in through the ports 28 as the sleeve 14 rotates, and discharged through the ports 30 and 31 at the top. The ports 28 and 29 and 30 and 31 are provided in sufficient number to allow the free circulation of the cooling agent, and they may be so located that when part of the ports 28 and 29 are out of communication with each other, other ports will be in registry, so that the inflow of the cooling agent will at no time be entirely obstructed or interrupted. A similar arrangement may be adopted for the ports 30 and 31.

The arrangement of the ports 10 and 12 at diametrically opposite points and the arrangement of the ports 24 and 25 90° apart is to be preferred, but obviously we may adopt a different arrangement if convenient. We prefer to locate the ports 10 and 12 and 24 and 25 so that one of each will be nearer to the head 3 than the other, because, by offsetting the ports in this way, the intake and exhaust ports can be most advantageously controlled, and any overlapping prevented; that is to say, one is not allowed to open until the other is entirely closed.

In case the engine is built with two cylinders or four, each pair of cylinders need only have one driving gear, as the pinion 21 can be arranged to drive two sleeves, one in

one direction and the other in another direction, thereby lessening the vibration caused by the revolution of the parts. Furthermore, our engine can be built in any ordinary machine shop without special machinery.

The valve sleeve is a self-oiler attachment, and by casting it hollow, as shown in Fig. 4, a proper cooling effect can be obtained.

We wish to have it understood that the embodiment of our invention on the drawings is illustrative only, and that we do not care to be limited to the exact details shown and described, but reserve to ourselves the right to make any changes in the shape, size and arrangement of the parts that fairly fall within the scope and spirit of our invention.

Having thus described our invention, we claim as new and desire to secure by Letters Patent:

1. In an internal combustion engine, a cylinder, a rotary tubular valve projecting through the cylinder and having flanges at its ends for holding it in the cylinder, the upper flange of the valve resting upon the end of the cylinder, and a cap-like head secured to and resting upon the upper end of the cylinder outside of the upper flange of the valve, said cap forming with the cylinder a chamber of greater diameter than that of the cylinder.

2. In an internal combustion engine, a cylinder having a flange at its lower end, an open ended rotary tubular valve projecting through the cylinder and having flanges at its ends, the flange at the upper end of the valve resting upon the end of the cylinder, a cap-like head secured to and resting upon the end of the cylinder outside of the flange of the valve and forming with the cylinder a chamber into which opens the upper end of the tubular valve, and a crank case secured to the cylinder between its flange and the flange of the valve.

3. In an internal combustion engine, a cylinder having inlet and exhaust ports at opposite sides and in different horizontal planes, a cap-like head on the cylinder and forming with the cylinder a chamber, an igniter carried by the head and projecting into the said chamber, an open ended tubular rotary valve in the cylinder and having flanges at its ends for holding it in the cylinder, said valve having ports located in different horizontal planes and spaced apart circumferentially of the valve, a piston in the valve, a crank shaft operatively connected with the piston and gearing for operating the valve from the crank shaft.

4. In an internal combustion engine, the combination of a hollow tubular valve member having an annular space in its wall to receive a cooling agent, and passages at its upper and lower ends leading to and from

and space, an engine having a chamber receiving said valve member and having ports registering with said passages to permit the cooling agent to flow to and from said space in the valve member, and a piston reciprocating in said valve.

To testimony whereof we have signed our

names to this specification in the presence of two subscribing witnesses.

GEORGE D. CASSON.
FRANK D. BLAKELY.
